BABY BOTTLE HOLDER

Filed Dec. 29, 1926

UNITED STATES PATENT OFFICE

CHARLES JOHNSTON SMITH, OF CHICAGO, ILLINOIS

BABY-BOTTLE HOLDER

Application filed December 29, 1926. Serial No. 157,657.

This invention pertains to a device for holding or supporting nursing bottles, toys and the like in front of a baby's face and where the baby may grasp the object held without difficulty. The invention will be disclosed in a device for holding a nursing bottle in such a manner that an infant may easily feed from the bottle without requiring that someone support the bottle while the baby is being fed and without placing the weight of the bottle and its contents on the baby's chest.

One of the primary objects of the invention is to provide a simple and inexpensive but efficient device so constructed and arranged that it will support a bottle in the proper position with respect to the baby and one which will receive its support from the weight of the baby's body. For this purpose the device includes a portion adapted to be disposed beneath the baby's shoulders when the baby is lying flat upon its back or otherwise reclining in a position for feeding where the possibility of dislodgment is minimized.

Many other objects including the advantages and novel features will be or should become readily appreciated after perusal of the description and claims taken in connection with the drawing in which:

Fig. 1 is a top plan view of one form of the invention, showing in dotted lines the position of a baby when the device is in use, and

Fig. 2 is a side elevation of the device shown in Fig. 1.

The illustrated form of the invention comprises an arm portion 2, a body portion 3 integral with the arm 2 at one of its ends, a standard generally designated 4, and a spring clip member 5 adapted to receive and support a bottle generally designated 6. The body and arm portions 2 and 3 are preferably formed of substantially rigid sheet metal or very heavy cardboard or the like and the body 3 is preferably made of substantially crescent shape with arcuate edges 7 and 8, as shown in Fig. 1. The upper surface of the body portion may in some forms of the invention, as illustrated, be slightly concave, although it is preferable that it be

55 nearly flat in order that the device may be disposed beneath the baby's shoulders when the latter is lying on the floor and the upper surface is preferably padded in any suitable manner, as shown at 9.

56 The standard 4 may be secured to and upright on the arm 2 in any suitable manner, but is preferably provided with a hinge 11 so that it may be disposed flat along the arm and body portions for convenience. The 60 standard above the hinge is made in three parts 12, 13 and 14, the portion 12 being hollow to receive a pintle 15 for vertical and 65 rotary adjustment of the portion 13 with respect thereto and having a thumb screw 16 for securing the portion 13 of the standard in adjusted position. The portion 13 at its upper end is bent into a substantially horizontal direction, as shown at 17, and is hollow as is the member 12 to receive a pintle 18 70 formed on the depending portion 14 for horizontal adjustment of the spring clip 5 and the bottle 6, the portion 14 being likewise securable in adjusted position by means of the thumb screw 19. The extreme lower end of the portion 14 is preferably provided with a ball 21 adapted to be received in a spherical socket provided by the two halves of the spring clip so that the bottle or other device held by the spring clip may be substantially 75 universally mounted.

76 The above described construction provides a very simple and efficient device. When it is to be used the body portion 3 with the padded surface uppermost and the concave edge 80 85 directed toward the head of the baby is disposed beneath the baby's shoulders. In this position, the arm 2 projects laterally, that is, outwardly from the side of the baby and the bottle. The bottle, when secured by 90 the spring clip 5, may be adjusted to a position where the nipple or bottle may be grasped by the baby and the nipple inserted into its mouth. Rubber tubing, if desired, may be slipped over the several parts of the standard of the arms of the spring clip 5, as 95 will be obvious.

100 While I have shown and described the invention in what is at present a preferred form and have also illustrated and described it

as particularly suitable for holding a baby's bottle, it will be apparent that it is susceptible of wide variation in construction and arrangement and useful in many other ways. Consequently, I do not desire to be limited by the construction illustrated and described but only by the spirit of the invention and the scope of the appended claims.

I claim:

10. 1. A baby bottle holder comprising, a body member of relatively stiff material formed in a substantially crescent shape, in plan, and of substantial breadth and provided with a concave edge, an arm element extending laterally with respect to the body member and secured thereto, a vertically disposed standard pivotally secured to said laterally extending arm and means to suspend a bottle by said standard, said means being adjustable to maintain the bottle in different angular positions, the body member being adapted to extend across and beneath the shoulders of the baby with the laterally extending arm portion protruding laterally therefrom.
15. 2. A baby bottle holder comprising a relatively stiff body member of substantially crescent shape, in plan, and of substantial breadth and provided with a concave edge, a laterally extending arm connected with said body portion, a standard secured to said arm and vertically disposed when in operative condition, a bottle holding means secured to said standard and adjustable to place the bottle in different angular and vertical positions with respect to the baby, said body portion being adapted to be disposed beneath the baby's shoulders with the concave edge thereof directed toward the baby's head and the laterally extending portion lying alongside the baby.
20. 3. A bottle holder of the character described, comprising a body member of relatively stiff material in substantially crescent shape and substantially flat and having a laterally extending arm, a vertically disposed standard hingedly secured to the arm so that it may be collapsed to the body member, a detachable bottle holding element secured to the upper portion of said vertical standard, said bottle holding member being adjustable to different relative positions with respect to the body member, the body member being shaped to conform and fit beneath the shoulders of the baby with the arm extending alongside the baby.

In witness of the foregoing I affix my signature.

C. JOHNSTON SMITH.
